UNITED STATES PATENT OFFICE.

WOODBURY K. DANA, OF WESTBROOK, MAINE.

VACUUM-HEAD FOR COTTON-PICKING MACHINES.

1,067,802.

Specification of Letters Patent. Patented July 22, 1913.

Application filed November 21, 1912. Serial No. 732,665.

To all whom it may concern:

Be it known that I, WOODBURY K. DANA, of Westbrook, in the county of Cumberland and State of Maine, have invented certain new and useful Improvements in Vacuum-Heads for Cotton-Picking Machines, of which the following is a specification.

My invention relates to that class of cotton picking machines which employ vacuum heads or nozzles with rotating picking tubes by which the cotton is twisted from the boll and drawn into the opening of the nozzle. Hitherto these picking tubes have been rotated either by means of flexible shafts mechanically operated or by vanes or blades fixed to the outside of the picking tube and operated by the in-rushing air currents. The former class of devices involved more or less complicated mechanism for rotating the flexible shafts and the latter class involved dividing the in-coming air into two parts with the result that the pressure at the mouth of the picking tube was materially reduced.

According to my invention I locate the blades of the rotary picking tube on the inside of the tube so that the single column of air performs the double function of rotating the tube and drawing in cotton.

Another feature of my invention is the peculiar arrangement of the picking teeth or fingers which are arranged at the edge of the mouth of the picking tube as herein-after particularly set forth.

I illustrate my invention by means of the accompanying drawing in which is shown the preferable form of my invention.

In the drawing, Figure 1 represents a central longitudinal section, Fig. 2 is an end view, and Fig. 3 is a side elevation showing the action of the nozzle on the cotton.

The vacuum nozzle is provided with means by which the cotton is seized and twisted as the nozzle is approached to the boll and whereby the cotton is released from the boll. This I prefer to do by means of an internal rotating picking tube provided with teeth which seize and twist the cotton releasing it easily from the boll.

Referring to Figs. 1, 2 and 3 of the drawing, *a* represents a vacuum head or nozzle here shown as cylindrical in form and connecting at its inner end with a suction hose *b*. The outer end of the nozzle is formed with a flange *c* for the purpose of diverting the entering current of air toward the inlet.

The nozzle is provided with an internal rotatable picking tube having teeth in its outer end whereby the cotton fibers are seized and twisted to remove them from the boll. As 60 here shown, the picking tube *d* has at each end an external ring or collar *d'* and *d''*, which are adjacent to internal annular shoulders *a'* and *a''* in the nozzle proper and balls *e* are interposed between the rings and 65 the shoulders forming ball bearings on which the picking tube *d* is supported and on which it rotates. At the outer end of the picking tube *d* which preferably projects somewhat beyond the end of the nozzle 70 proper, are teeth which are adapted to engage the cotton fibers. These teeth are preferably on the inner surface and just within the end and as here shown, they consist of sharpened pins *h* set in the picking tube near the end and inclining slightly rearward or in direction in which the air is moving. They also incline somewhat from a radial direction making an acute angle 75 with and in the direction of the line of motion of the edge of the tube so that as the picking tube revolves they tend to engage the cotton fibers but easily release them as they are drawn inward. Means are provided to rotate the picking tube while the 80 machine is in operation. As shown the interior surface of the picking tube is provided with a series of inclined fan blades *f* which act to rotate the picking tube as the 85 air and cotton pass inward.

In operation the suction head is connected to the end of a suction hose and approached to the cotton boll. The rotating teeth seize the cotton fibers which are drawn toward it by suction and by twisting the 90 cotton from the boll.

The vacuum head above described combining as it does the rotation of the picking tube with its cotton engaging teeth and the 95 force of the in-rushing air, readily frees the cotton from the boll.

It is to be understood that as many of these vacuum heads are used as are necessary and that they are connected with a 100 suitable exhaust fan.

I claim:

1. A nozzle for pneumatic cotton picking machines including an outer tube and an inner independently freely rotatable tube, 110 through which the air and cotton pass, diagonally disposed blades mounted within

the inner tube whereby said tube is rotated by the inrushing air.

2. A nozzle for pneumatic cotton picking machines including a rotary picking tube through which the air and cotton pass, said tube having internal diagonally disposed blades and a series of picking teeth surrounding the mouth of said tube said teeth inclining rearwardly and inwardly at an

acute angle with and in the direction of the 10 line of rotary motion.

In testimony whereof I have affixed my signature, in presence of two witnesses.

WOODBURY K. DANA.
